HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed December 20, 1923. Serial No. 681,742.

My invention relates to railway traffic controlling apparatus.

I will describe one form and arrangement of apparatus embodying my invention, and will then point out the novel features thereof in claims.

In the accompanying drawings, Fig. 1 is a diagrammatic view showing one form of trackway apparatus embodying my invention. Fig. 2 is a diagrammatic view showing one form of governing means suitable for co-operation with the trackway apparatus shown in Fig. 1 and also embodying my invention.

Similar reference characters refer to similar parts in each of the views.

Referring first to Fig. 1, the reference characters 1 and 1^a designate the track rails of a railway over which traffic normally moves in the direction indicated by the arrow. The stretch of track here shown comprises a track section A—B which section is separated from the rest of the stretch by means of insulated joints 2. Track circuit current is at times supplied to section A—B by a track transformer designated by the reference character T and having its secondary 3 connected across the rails adjacent the exit end of the section.

The supply of energy to the primary 4 of transformer T is controlled by a coding device or code impulse transmitting device D and a selector device C. The coding device may be of any suitable form and as here shown comprises a constant speed motor device 17 such as a synchronous motor. This motor is constantly supplied with alternating current from the secondary 5 of a line transformer E. The primary 6 of this transformer E is constantly supplied with alternating current from a suitable source, such as an alternator G, over line wires 7 and 7^a. A plurality of code wheels 8, 9, 10, etc., are mechanically and electrically connected together by means of a shaft 115, and this shaft is rotated by motor 17 thus causing the wheels also to turn. Referring particularly to code wheel 8, this wheel is provided, at its circumference, with a plurality of outstanding contact teeth 16 disposed at inter-

vals around the edge of the wheel. A fixed contact member 8^a is so disposed with respect to wheel 8 that as the wheel is rotated by motor 17 the fixed contact 8^a engages successively the contacts 16 on wheel 8. The remaining code wheels 9, 10, 11, 12, 13 and 14 are each provided with fixed contacts 9^a, 10^a, 11^a, 12^a, 13^a, and 14^a, respectively, and carry outstanding contacts 16 arranged to engage the associated fixed contact in the manner just described in connection with wheel 8. For purposes of clearness the contacts 16 have been much enlarged in the drawing and it is understood that in practice the time during which the fixed contact engages a single contact 16 of the associated code wheel would be very brief.

The selector C comprises a movable contact arm 15 arranged to selectively engage a plurality of fixed contact members, one for each code wheel. For example, contact 8^b is connected with fixed contact 8^a of code wheel 8, contact 9^b is connected with fixed contact 9^a of code wheel 9, and so on, as will be apparent from the drawing. The movable contact arm 15 of selector C may be operated in any desired manner as by traffic conditions in advance, or by means controlled from a distant point.

As shown in the drawing, arm 15 of selector C engages contact 14^b, and a circuit is closed which passes from the secondary 5 of line transformer E, through wire 18, shaft 115, code wheel 14, fixed contact 14^a, wire 19, contact 14^b—15 of selector C, wire 20, primary 4 of track transformer T, and wire 21 back to transformer E. When arm 15 of selector C is moved to other positions the circuit is the same except that other code wheels are substituted for code wheel 14, depending upon which contact is engaged by arm 15. Since coding device D operates continuously, it follows that the circuit for primary 4 of transformer T is intermittently closed as the projections 16 of the code wheel included in its circuit successively engage the associated fixed contact. The projecting contacts 16 are arranged in different relation on the different wheels to give different codes. For example, the contacts 16 on

wheel 8 are arranged at regular intervals around the circumference of the wheel. When contact 15—8^b of selector C is closed, therefore, section A—B is supplied with energy in the form of successive groups of alternating current impulses, each group being separated from the preceding group by a regular time interval of, for example, one second. Under this condition section A—B 5 is supplied with what I shall term "code 8." When contact 15—9^b of selector C is closed, code wheel 9 is included in the circuit for transformer T and section A—B is then supplied with what I shall term "code 9." This 10 code as shown consists of groups of impulses, each group separated from the preceding group by alternate time intervals of one second and two seconds. In a similar manner code wheel 10 gives a "code 10," characterized by alternate intervals of one second and 15 three seconds, "code 11" given by code wheel 11 consists of regular intervals of two seconds between successive groups of impulses, "code 12" given by code wheel 12 20 consists of groups of impulses separated by alternate time intervals of two seconds and three seconds, "code 13" given by code wheel 13 consists of regular time intervals of three seconds between consecutive groups 25 of impulses, and "code 14" given by code wheel 14 consists of time intervals of one second, two seconds and three seconds, following each other in order between successive groups of impulses. In each case it 30 should be noted that the length of time during which energy is supplied continuously to the section is relatively brief and substantially the same for all codes, the differentiation between the different codes being obtained by the different time intervals 35 between such periods of energization.

Referring now to Fig. 2, in the form here shown the apparatus for governing traffic in response to the code supplied to the track-way is carried on a vehicle. Mounted transversely with respect to the rails 1 and 1^a, at some convenient point on the vehicle, as in front of the forward axle 22 of the vehicle as shown diagrammatically in Fig. 1, are 40 two magnetizable cores H and H^a. Core H is provided with a winding 23 and core H^a is provided with a similar winding 23^a. The two windings, comprising what I shall term the "track coil," are so connected that the 45 voltages induced in the windings by currents flowing in the opposite directions in the two track rails at a given instant are additive. The terminals *c* and *d* of the track coil are connected, through suitable amplifying apparatus 24 and a rectifier 25, with the winding of a relay K, which for purposes of simplicity I will term the "main relay." The rectifier 25 may be of any suitable form and serves to change the periodic currents induced in the track coil and amplified by app-

aratus 24 into substantially uni-directional current which is supplied to relay K. The main relay K is responsive to uni-directional current to control certain contacts as will appear hereinafter.

Associated with relay K is a selector which in the form shown herein is a time measuring device designated by the reference character X. This device may be of any suitable form and as here shown comprises a motor element 26 and a movable contact finger 27 operated thereby. The parts are so proportioned that when motor element 26 is continuously energized for a period of approximately three seconds, contact 27—28 is closed, when motor element 26 is continuously energized for approximately two seconds contact 27—29 is closed, when motor element 26 is continuously energized for approximately one second, contact 27—30 is closed, and when motor element 26 is de-energized, contact finger 27 after a very brief interval moves to its lower position in which contacts 27—28, 27—29, and 27—30 are all open. When motor element 26 is continuously energized for a period of time greater than three seconds contact finger 27 moves to an extreme upper position and contacts 27—30, 27—29, and 27—28 are all open. This motor element 26 is provided with a circuit which passes from a suitable source of energy, such as battery L, through wire 34, back contact 33 of main relay K, wire 32, winding of motor element 26 of time measuring device X, and wire 31 back to battery L. It is clear that this circuit is closed, and hence that motor element 26 is energized, only when main relay K is de-energized.

Three slow releasing relays, designated by the reference characters N, O and P, respectively, are controlled by time measuring device X and main relay K as follows: In addition to contact 33, main relay K also operates a movable contact finger 35 which is arranged to engage with two fixed contacts 36 and 37 in such manner that when relay K is energized finger 35 engages contact 36 only, when relay K is deenergized finger 35 engages contact 37 only; but for a brief interval during each movement of finger 35 from its upper to its lower position, or vice versa, finger 35 engages both contacts 36 and 37 simultaneously.

In explaining the operation of the slow releasing relays N, O and P, I will assume that the section A—B of Fig. 1 is being supplied with code 8, that is, with successive groups of impulses separated by time intervals of one second, and that a vehicle V equipped with apparatus similar to that shown in Fig. 2 occupies the section. It is plain that when a group of impulses is being supplied to the trackway, an alternating voltage will be induced in the pick-up coil comprising windings 23 and 23^a. The energy so

- induced in the pick-up coil is amplified and rectified and serves to supply current to relay K which thereupon becomes energized. When relay K is energized, motor element 26 is de-energized and all the contacts of the time measuring device are thereby opened. When next in succession relay K is de-energized during the interval between successive groups of impulses, motor element 26 is energized, and since this interval is of substantially one second duration, contact 27-30 becomes closed. When relay K is again energized, contact 36-35-37 of relay K closes for an instant before contact 27-30 of device X opens and current is momentarily delivered to relay N over a circuit which passes from battery L through wires 34 and 38, contact 36-35-37 of relay K, wire 39, contact 27-30 of device X, wire 44, winding of slow releasing relay N, and wires 40 and 31, back to battery L. This current causes relay N to become energized and, due to its slow releasing characteristics an interval of time elapses before the relay again opens its front contacts. The parts are so designed and proportioned that this time interval is slightly greater than the maximum time between impulses delivered to the same relay. With the apparatus here shown the maximum time between successive impulses to any one relay is six seconds. It will thus be clear that as long as the vehicle occupies a stretch of track to which code 8 is being supplied, the front contacts of relay N will be continuously closed and hence the relay can be said to be continuously energized.
- Similarly if the section occupied by the train is supplied with code 11, relay K will be briefly energized at regular intervals of two seconds. The operation of device X is the same as in the case of code 8 except that the longer intervals of de-energization of relay K allow device X to close contact 27-29 and therefore each time relay K is energized a surge of current is delivered to relay O over a circuit which passes from battery L, through wires 34 and 38, contact 37-35-36 of relay K, wire 39, contact 27-29 of device X, wire 41, winding of relay O and wires 40 and 31 back to battery L. Each such surge of energy energizes relay O which thus maintains its front contacts closed as explained in connection with relay N, as long as the section is supplied with code 11.
- If the section is supplied with code 13, relay P is energized at intervals of three seconds over a circuit which passes from battery L, through wires 34 and 38, contact 36-35-37 of relay K, wire 39, contact 27-28 of device X, wire 42, winding of relay P, and wires 40 and 31 back to battery L. As explained in connection with relay N, relay P due to its slow releasing feature maintains its front contacts closed during the time interval between successive energizations.

It will be clear from the foregoing that if code 9 is supplied to the section, relay K is de-energized for alternate periods of one and two seconds and that relays N and O are therefore alternately energized. These relays are, therefore, both held in the energized position as long as this code is supplied to the track. Similarly, when code 10 is supplied to the track, relays N and P are both energized, when code 12 is supplied to the track, relays O and P are both energized, and when code 14 is supplied to the section all three relays N, O and P are constantly held in the energized position.

It should be pointed out that the time intervals of one second, two seconds and three seconds have been used only for purposes of explanation, and that any other suitable time intervals could be used equally well. The vehicle carried apparatus must, of course, be proportioned and designed so as to respond to the time intervals chosen for the codes supplied to the track section. If time intervals are so chosen that slow acting relays N, O and P of the usual copper sleeve type do not have sufficiently long releasing periods, some suitable form of mechanical or pneumatic slow releasing device or run-down device may be interposed between the winding of each relay and the contacts which it controls.

Although in the form of apparatus illustrated herein the various codes are distinguished from each other by the lengths of the time intervals between groups of impulses, this specific form is not essential to my invention. Any other means may be used to distinguish the various codes, such for example as groups of impulses of various lengths.

The three slow releasing relays N, O and P may be used to control governing means on the vehicle in any desired manner. As shown in the drawing these relays control the brakes on the vehicle through the medium of a magnet valve M adapted to apply the brakes when de-energized, and a speed governing device R. In the form here shown the speed governing device R comprises a centrifuge S operated in accordance with the speed of the vehicle. This centrifuge comprises a rotating shaft 45 to which a collar 50 is rigidly fastened. A second collar 48 is free on shaft 45 and is biased to its upper position by a spring 47. Two weights 46 are secured to collars 48 and 50 by means of linkwork. When shaft 45 rotates due to motion of the vehicle, weights 46 move outward as a result of centrifugal force and collar 48 is drawn downward against the bias of spring 47 by an amount which increases in accordance with increases in the speed of the vehicle. It follows that there is one, and only one, position of collar 48 for any speed of the vehicle. A contact lever 49 is pivoted at point 49^a and has its left hand extremity connected me-

chanically with collar 48. As the speed of the vehicle increases, the right hand end of lever 49 therefore moves upward.

A plurality of fixed contact sectors are arranged to cooperate with lever 49, and these sectors are so arranged as to control certain hereinafter named circuits in accordance with the speed of the vehicle. For example, the dotted lines radiating from point 49^a in the drawing may represent various positions of lever 49 according to various speeds of the vehicle, the vehicle speed corresponding to each position being indicated in miles per hour. As here shown, when the speed of the vehicle is in excess of 90 miles per hour, lever 49 does not engage any of the contact segments. When the speed is 90 miles per hour or less, contact 49—51 is closed, when the speed is 75 miles per hour or less contact 49—52 is closed, when the speed of the vehicle is 60 miles per hour or less contact 49—53 is closed and so on. It will be noticed that when the vehicle is at rest, the right hand side of lever 49 will occupy its lower position and will engage all the sectors 51, 52, 53, 54, 55, 56 and 57 simultaneously.

When the vehicle is being supplied with code 14, relays N, O and P are all energized, and a circuit is closed passing from battery L, through wire 34, front contact 58 of relay P, wire 59, front point of contact 60 of relay O, wire 61, front contact 62 of relay N, wires 63 and 64, contact 49—51 of device R, wire 65, magnet valve M, and wire 31 back to battery L. It is evident that if the speed of the train exceeds 90 miles per hour this circuit will be broken at contact 49—51 of device R and the resulting de-energization of magnet M will cause a brake application. The circuit just traced is provided with a branch which passes from wire 63 through an indicator such as an electric lamp 66, and wire 43 to wire 31. It follows that as long as code 14 is supplied to the vehicle, lamp 66 is lighted, thus informing the operator of the vehicle of the speed limitation under which he is running.

If the vehicle is being supplied with code 12, relays O and P are energized and relay N is de-energized. Under these conditions a circuit passes from battery L, through wires 34, 67 and 68, front contact 69 of relay O, wire 70, back contact 71 of relay N, wire 72, front point of contact 73 of relay P, wires 74 and 75, contact 49—52 of device R, wire 65, magnet valve M and wire 31 back to battery L. If the speed of the vehicle exceeds 75 miles per hour this circuit is broken at contact 49—52 of device R and the brakes will be applied. The circuit just traced is provided with a branch which passes from wire 74, through lamp 76 and wires 117, 43 and 31 back to battery L. It follows that when this lamp is lighted it informs the operator of the vehicle that if he exceeds 75 miles per hour, the brakes will be applied.

I will next assume that the speed of the vehicle is below 60 miles per hour and that the section occupied by the vehicle is being supplied with code 10. Under these conditions relay O is de-energized and relays N and P are energized, and a circuit is closed over which current passes from battery L, through wire 34, front contact 58 of relay P, wire 59, back point of contact 60 of relay O, wire 77, front point of contact 78 of relay N, wires 79 and 80, contact 49—53 of device R, wire 65, magnet valve M, and wire 31 back to battery. If the vehicle exceeds a speed of 60 miles per hour under these conditions the brakes will be applied by the opening of contact 49—53 of device R. A branch is provided for the circuit just traced which passes from wire 79, through lamp 81 and wires 117 and 43 back to wire 31. The lamp 81 therefore remains lighted as long as the vehicle receives code 10.

I will next assume that the speed of the vehicle is below 50 miles per hour and that the vehicle is receiving code 9. Under these conditions relay P is de-energized and relays N and O are energized. A circuit is therefore closed over which current passes from battery L, through wires 34 and 67, front contact 82 of relay N, wire 83, back contact 84 of relay P, wire 85, front point of contact 86 of relay O, wires 87 and 88, contact 49—54 of device R, wire 65, magnet valve M, and wire 31 back to battery L. This circuit is provided with a branch from wire 87, through lamp 89 and wires 117 and 43 back to wire 31. If the vehicle speed exceeds 50 miles per hour, the brakes will be applied by the opening of contact 49—54 of device R but lamp 89 burns continuously as long as the vehicle is supplied with code 9.

If relays N and O are both de-energized and relay P is energized, as when the vehicle is receiving code 13, and if the speed of the train is below 40 miles per hour, magnet valve M is energized over the following circuit: from battery L, through wire 34, front contact 58 of relay P, wire 59, back point of contact 60 of relay O, wire 77, back point of contact 78 of relay N, wires 90 and 91, contact 49—55 of device R, wire 65, magnet valve M, and wire 31 back to battery L. If the vehicle exceeds a speed of 40 miles per hour, however, this circuit is broken and the brakes are applied. A branch for the circuit just traced, passes from wire 90, through lamp 92 and wires 117 and 43 back to wire 31. This lamp 92 is therefore energized as long as the vehicle receives code 13.

Another circuit for magnet valve M passes from battery L, through wires 34, 67 and 68, front contact 69 of relay O, wire 70, back contact 71 of relay N, wire 72, back point of contact 73 of relay P, wires 94 and 95, contact 49—56 of device R, wire 65, magnet valve M, and wire 31 back to battery L. A branch for this circuit passes from wire 94, through

lamp 96 and wires 117 and 43, back to wire 31. This circuit for magnet valve M is closed only when the speed of the vehicle is below 30 miles per hour, and relays N and P are de-energized and relay O is energized, as when the train is receiving code 11, but lamp 96 is continuously energized as long as the vehicle receives code 11 and irrespective of the vehicle speed.

10 If the vehicle is not proceeding at a speed in excess of 20 miles per hour and is receiving code 8, the circuit for magnet valve M may be traced from battery L, through wires 34 and 67, front contact 82 of relay N, wire

15 83, back contact 84 of relay P, wire 85, back point of contact 86 of relay O, wires 97 and 98, contact 49—57 of device R, wire 65, magnet valve M, and wire 31 back to battery L. If the speed of the vehicle exceeds 20 miles

20 per hour, the opening of contact 49—57 of device R de-energizes magnet valve M and applies the brakes. The circuit thus traced is provided with a branch passing from wire 97, through lamp 99 and wires 117 and 43 back to wire 31. The lamp 99 therefore burns as long as the train receives code 8.

When the portion of track occupied by the vehicle is continuously supplied with alternating current relay K is continuously energized and motor element 26 is de-energized. When, however, the portion of track occupied by the vehicle is supplied continuously with direct current or if the supply of current is discontinued, relay K is continuously de-energized and motor element 26 of device X is constantly energized. In either case however, all contacts 27—28, 27—29, and 27—30 of device X will be open. Relays N, O and P will, therefore, all be de-energized, 40 all the indicators will be extinguished, and the brakes will be applied irrespective of the speed of the vehicle.

Each of the indicators 66, 81, 92, 76, 96, 45 89 and 99 may be provided with a suitable index, as a ground glass cover bearing a suitable legend, or by coloring the cover glass with a distinctive color, to inform the operator of the train as to the meaning of any particular indicator.

50 Although I have particularly described certain speeds and referred to them arbitrarily, it should be pointed out that these particular speeds are not essential.

It is not necessary to carry each of the 55 circuits through the speed governing device R and the magnet valve M, but some may be utilized only to light indicators for the purpose of informing the operator of the vehicle concerning traffic conditions in advance or 60 for transmitting special intelligence of any form from the trackway to a moving vehicle.

If sufficient indications can not be transmitted with the seven possible codes here shown, additional slow-releasing relays similar to relays N, O and P may be added, each

relay being controlled by a separate contact on device X. For example, by adding a fourth relay, fifteen separate and distinct indications may be used, with five slow-releasing relays, thirty-one indications, and so on. 70

Although I have herein shown and described only one form and arrangement of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising means for supplying the trackway with impulses spaced by time intervals of which adjacent time intervals are of different lengths, and train-carried governing means comprising time measuring means responsive to the lengths of such intervals. 85

2. Railway traffic controlling apparatus comprising means for supplying the trackway with different codes one of which comprises energy impulses spaced by equal time intervals, and another of which comprises energy impulses spaced by time intervals of which adjacent intervals are unequal, and train carried governing means comprising 90 time measuring means responsive to the lengths of such intervals. 95

3. Railway traffic controlling apparatus comprising means for supplying the trackway with codes consisting of groups of impulses separated by time intervals adjacent time intervals of one code being equal, and adjacent time intervals of another code being unequal, time measuring means responsive to the lengths of such intervals, speed measuring 100 means on a vehicle, and traffic governing means on the vehicle controlled by said time measuring means and by said speed measuring means. 105

4. Railway traffic controlling apparatus comprising means for supplying the trackway with impulses spaced by time intervals adjacent time intervals being of different lengths, a first slow releasing relay energized at the expiration of such interval of one 115 length, a second slow releasing relay energized at the expiration of such interval of a different length, and traffic governing means controlled by said relays. 115

5. Railway traffic controlling apparatus comprising means for supplying the trackway with code signals made up of groups of impulses each group being separated from the preceding group by a time interval, time measuring means selectively responsive to the 120 lengths of said intervals, speed measuring means on a vehicle, and traffic governing means controlled by said time measuring means and said speed measuring means. 125

6. Railway traffic controlling apparatus 130

- comprising means for supplying the trackway with code signals made up of groups of impulses, each group being separated from the preceding group by a time interval, a 5 plurality of slow releasing relays, means for energizing any relay or combination of relays in accordance with the lengths of such time intervals, and traffic governing means controlled by said slow releasing relays.
10. Railway traffic controlling apparatus comprising means for supplying the trackway with code signals made up of groups of impulses, each group being separated from the preceding group by a time interval, a 10 plurality of slow releasing relays, means for energizing only predetermined ones of such relays in accordance with the lengths of such intervals, and traffic governing means controlled by said relays.
15. In combination, time measuring means on a vehicle comprising a plurality of contacts, means in the trackway for repeatedly closing any one of said contacts, or for repeatedly closing any combination of said contacts in order, a slow releasing relay controlled by each said contact, and traffic governing means controlled by said relays. 20
25. Railway traffic controlling apparatus comprising means for supplying the trackway with code signals made up of groups of impulses, each group being separated from the preceding group by a time interval, a vehicle carried relay energized by said groups of impulses but de-energized during said time intervals, a contact on said relay closed only for a brief instant adjacent the middle of each stroke of said relay, time measuring means controlled by said relay, slow releasing relays controlled by said first relay and 30 by said time measuring means, and traffic governing means controlled by said slow releasing relays. 35
40. Railway traffic controlling apparatus comprising a plurality of contacts on a rail- 45 way vehicle, means including a time measuring device on the vehicle and timed impulse transmitting apparatus in the trackway for selectively closing one or more of said contacts, and governing mechanism on the vehicle controlled by said contacts. 50
45. Railway traffic controlling apparatus comprising a plurality of contacts on a rail- 55 way vehicle, selecting means on the vehicle for selectively closing any one or more of said contacts, code impulse transmitting means in the trackway for causing operation of said selecting means, and governing mechanism on the vehicle controlled by said contacts. 60
50. Railway traffic controlling apparatus comprising a plurality of groups of contacts on a railway vehicle, time measuring select- 65 ing means on the vehicle for selectively closing the contacts of any group or any combination of groups, code impulse transmitting means in the trackway for causing operation of said selecting means, and governing mechanism on the vehicle controlled by said contacts. 70
55. Railway traffic controlling apparatus comprising a stretch of railway track, means for selectively supplying said stretch with a plurality of impulse codes, a plurality of groups of contacts on a railway vehicle, selecting means on the vehicle including time measuring means arranged to close the contacts in any group or combination of groups in accordance with the code supplied to the trackway, and governing means on the vehicle controlled by said contacts. 75
60. Railway traffic controlling apparatus comprising three relays on a railway vehicle, time measuring selecting means on the vehicle for operating any relay or combination of relays, code impulse transmitting means in the trackway for controlling said selecting means, and governing mechanism on the vehicle controlled by said relays. 80
65. Railway traffic controlling apparatus comprising three relays on a railway vehicle, time measuring selecting means on the vehicle for operating any relay or combination of relays, code impulse transmitting means in the trackway for controlling said selecting means, speed responsive means on the vehicle, and governing mechanism on the vehicle controlled by said speed responsive means and by said relays. 85
70. Railway traffic controlling apparatus comprising three relays on a railway vehicle, selecting means on the vehicle for operating any relay or combination of relays, code impulse transmitting means in the trackway for controlling said selecting means, speed responsive means on the vehicle, and brake applying apparatus on the vehicle controlled by said speed responsive means and by said relays. 90
75. Railway traffic controlling apparatus comprising three relays on a railway vehicle, selecting means on the vehicle for operating any relay or combination of relays, code impulse transmitting means in the trackway for controlling said selecting means, speed responsive means on the vehicle, and brake applying apparatus on the vehicle controlled by said speed responsive means and by said relays. 95
80. Railway traffic controlling apparatus comprising three relays on a railway vehicle, selecting means on the vehicle for operating any relay or combination of relays, code impulse transmitting means in the trackway for controlling said selecting means, speed responsive means on the vehicle, and brake applying apparatus on the vehicle controlled by said speed responsive means and by said relays. 100
85. Railway traffic controlling apparatus comprising three relays on a railway vehicle, selecting means on the vehicle for operating any relay or combination of relays, code impulse transmitting means in the trackway for controlling said selecting means, speed responsive means on the vehicle, and brake applying apparatus on the vehicle controlled by said speed responsive means and by said relays. 105
90. Railway traffic controlling apparatus comprising three relays on a railway vehicle, selecting means on the vehicle for operating any relay or combination of relays, code impulse transmitting means in the trackway for controlling said selecting means, speed responsive means on the vehicle, and brake applying apparatus on the vehicle controlled by said speed responsive means and by said relays. 110
95. Railway traffic controlling apparatus comprising three relays on a railway vehicle, selecting means on the vehicle for operating any relay or combination of relays, code impulse transmitting means in the trackway for controlling said selecting means, speed responsive means on the vehicle, and brake applying apparatus on the vehicle controlled by said speed responsive means and by said relays. 115
100. In combination, time measuring means on a vehicle comprising a plurality of contacts, means in the trackway for operating said time measuring means to repeatedly close any one of said contacts or to repeatedly close any combination of said contacts in order, and traffic governing mechanism controlled by said contacts. 120
105. In combination, time measuring means on a vehicle, means located in the trackway for causing repeated operation of said time measuring means, consecutive operations be- 125

ing for the same lengths of time or for different lengths of time according to traffic conditions, and traffic governing mechanism controlled by said time measuring means.

5 20. Railway traffic controlling apparatus comprising time measuring means having a plurality of contacts, trackway means for operating said time measuring means to repeatedly close any one of said contacts or to 70 repeatedly close any combination of said contacts in order, and traffic governing mechanism controlled by said contacts.

10 21. Railway traffic controlling apparatus comprising time measuring means, trackway 75 means for causing repeated operation of said time measuring means, consecutive operations being for the same lengths of time or for different lengths of time according to traffic conditions, and traffic governing mechanism controlled by said time measuring means.

15 22. Railway traffic controlling apparatus comprising time measuring means having a plurality of contacts, trackway means for 80 operating said time measuring means to repeatedly close any one of said contacts or to repeatedly close any combination of said contacts in succession, slow releasing relays controlled by said contacts, and traffic governing mechanism controlled by said relays.

25 23. Railway traffic controlling apparatus comprising means for supplying the trackway with impulses spaced by time intervals of which adjacent intervals are of different 85 lengths, time measuring means selectively responsive to the lengths of such intervals, and traffic governing mechanism controlled by said time measuring means.

30 24. Railway traffic controlling apparatus comprising means for supplying the trackway with different codes one of which comprises energy impulses spaced by equal time intervals, and another of which comprises energy impulses spaced by time intervals of 90 which adjacent intervals are unequal, time measuring means selectively responsive to the lengths of such intervals, and traffic governing mechanism controlled by said time measuring means.

35 25. Railway traffic controlling apparatus comprising a plurality of contacts, time measuring means for selectively operating any one of said contacts or any combination of said contacts, code impulse transmitting means 95 in the trackway for causing operation of said time measuring means, and traffic governing mechanism controlled by said contacts.

40 26. A railway signalling system including a stretch of track, means for connecting electrical energy intermittently across the track rails at suitably spaced points, said means operating to connect energy at said points asynchronously, and signaling means for said stretch responsive to said energy.

45 27. In an automatic train control system,

means for communicating influences corresponding to traffic conditions from the trackway to a moving vehicle comprising a continuously driven trackway commutator for connecting energy from a wayside source to the track rails and interrupting said energy at a recurrent series of time-spaced intervals of predetermined succession, car-carried means for inductively receiving said energy from the track rails, and rotary car-carried apparatus responsive to said interruptions in said energy, said car-carried apparatus being periodically synchronized with said trackway commutator.

28. In an automatic train control system, 80 means for communicating influences corresponding to traffic conditions from the trackway to a moving vehicle comprising a plurality of continuously driven trackway commutators for connecting electrical energy 85 to the track rails and interrupting said energy at recurrent pre-arranged time intervals, said intervals being differently arranged on said different commutators in accordance with traffic conditions ahead, trackway means for selectively connecting said commutators to interrupt said energy in accordance with traffic conditions, car-carried means for inductively receiving said electrical energy from the track rails, and rotary 90 car-carried apparatus responsive to said interruptions in said energy for indicating said traffic conditions ahead on the vehicle.

29. In an automatic train control system, 100 means for communicating influences corresponding to traffic conditions from the trackway to a moving vehicle comprising trackway apparatus for impressing electrical energy on trackway conducting means and interrupting said energy at recurrent intervals, 105 said intervals being spaced in a definite pre-arranged manner, car-carried means for inductively receiving said energy, and car-carried apparatus responsive to said interruptions of said energy, said car-carried apparatus being operated synchronously with said trackway apparatus.

30. In an automatic train control system, 110 means for communicating influences corresponding to traffic conditions from the trackway to a moving vehicle comprising trackway apparatus for impressing alternating current on the track rails and for recurrently interrupting said alternating current at a pre-arranged series of time-spaced intervals, 115 said series of intervals being controlled in accordance with traffic conditions ahead, car-carried means for inductively receiving said alternating current and car-carried apparatus for responding to said interruptions in 120 said current and actuating indicating means in accordance with traffic conditions ahead as represented by said interruptions.

31. A vehicle control system comprising, a plurality of contacts on a vehicle; means in- 125 130

cluding a time measuring device on the vehicle and timed impulse transmitting apparatus inductively influencing said device for selectively closing one or more of said contacts, and indicating devices on the vehicle selectively controlled by said contacts.

32. A vehicle control system comprising, three relays on a vehicle, time measuring selecting means on the vehicle for operating any relay or combination of relays, code impulse transmitting means for inductively controlling said selecting means, and indicating mechanism on the vehicle controlled by said relays.

15 33. A vehicle control system comprising time measuring selecting means on the vehicle including a plurality of contacts, timed code transmitting means for inductively influencing said selecting means to cause operation thereof to close repeatedly any one of said contacts or combination of said contacts, and indicating devices on the vehicle selectively controlled by said contacts.

34. A vehicle control system comprising, 25 a conductor, means for energizing said conductor with alternating current impulses arranged in different codes, one code comprising impulses spaced by equal time intervals, another code comprising impulses spaced by 30 time intervals of which adjacent intervals are unequal, time measuring means on the vehicle inductively influenced by the energization of said conductor and including contacts selectively closed in response to said 35 codes, and indicating devices on the vehicle controlled by said contacts.

35. In combination with the rails of a rail-way track, a rotating electric motor, a plurality of circuit controllers operated thereby, 40 the rate of operation of each circuit controller being different from the rate of operation of each of the other circuit controllers, and means for supplying alternating train governing current to said track rails through 45 any selected one of said circuit controllers.

36. In combination with the rails of a rail-way track, a rotating electric motor, a plurality of circuit controllers operated by said motor and each periodically closed while 50 the motor is in operation, the periodicity of each circuit controller being different from that of each of the other circuit controllers, and means for supplying alternating train governing current to said track rails through 55 any selected one of said circuit controllers.

37. In combination with the rails of a rail-way track, a rotating electric motor, a plurality of drums operated by said motor and all rotating at the same speed, each drum 60 constituting an element of a circuit controller which is periodically closed while the drum is in operation, and the periodicity of each circuit controller being different from that of each of the other circuit controllers, 65 and means for supplying alternating train

governing current to said track rails through any selected one of said circuit controllers.

38. In combination with the rails of a rail-way track, a rotating electric motor, a plurality of drums operated by said motor and all rotating at the same speed, a circuit controller associated with each drum and periodically closed while the drum is rotating, the periodicity of each circuit controller being different from that of each of the other 75 circuit controllers, and means for supplying alternating train governing current to said track rails through any selected one of said circuit controllers.

39. In combination with the rails of a rail-way track, a rotating electric motor, a plurality of drums all rotated at the same speed by said motor and each drum having a different number of projections, a circuit controller associated with each drum and closed 85 as many times during a revolution of the drum as there are projections on the drum, and means for supplying alternating train governing current to said track rails through any selected one of said circuit controllers. 90

In testimony whereof I affix my signature.

HERBERT A. WALLACE.
